CLAIM

The ornamental design for a carrier bag for flowers, as shown and described.

DESCRIPTION

FIG. 1 is a perspective view of my new and ornamental design for a carrier bag for flowers;

FIG. 2 is a side view thereof;

FIG. 3 is a front view thereof;

FIG. 4 is a top view thereof;

FIG. 5 is a bottom view thereof; and,

FIG. 6 is a side view of the carrier bag when holding flowers.

The broken lines shown in the drawings are for illustrative purposes only and form no part of the claimed design.
